(57) **CLAIM**

The ornamental design for a utensil grip, as shown and described.

DESCRIPTION

In a preferred embodiment, the nature of this product is as a handle for a utensil used in food preparation, such as for a spoon, slotted spoon, spatula, ladle or strainer.

FIG. 1 is a top, front, left perspective view of a utensil grip according to our new design;

FIG. 2 is a right side elevational view thereof; the left side elevational view being a mirror image;

FIG. 3 is a top plan view thereof;

FIG. 4 is a back end elevational view thereof; and,

FIG. 5 is a bottom plan view thereof.

The broken line representations in the figures are for the purpose of illustration only and form no part of the claimed design.
